Primary Examiner — Catherine A Tuttle(74) *Attorney, Agent, or Firm* — Greenberg Traurig, LLP(57) **CLAIM**

The ornamental design for an aerosol dispenser, as shown and described.

DESCRIPTION

FIG. 1 is a top, front and side perspective view of an aerosol dispenser showing our new design;

FIG. 2 is a front elevational view thereof;

FIG. 3 is a rear elevational view thereof;

FIG. 4 is a side elevational view thereof;

FIG. 5 is a right side elevational view thereof;

FIG. 6 is a top plan view thereof; and,

FIG. 7 is a bottom plan view thereof.

The broken lines depict the bottom end region that forms no part of the claimed design.
